ABSTRACT OF THE DISCLOSURE

A smooth working assembly including a number of standard parts is provided by positioning the parts in such space relationship as to avoid practically all of the many objections to gas burners for small outdoor incinerators. The primary purpose is to arrange the parts so that minimum attention need be given the assembly.

A main gas burner is connected to a source of gas by a passageway having in it a safety valve for shutting off the flow of gas in event of flame failure. The main gas burner has a discharge head and a pilot is located adjacent that discharge head. A thermocouple bears a particular relation to the pilot, which particular relation is characterized by the fact that the thermocouple is energized by the adjacent pilot, both of which are positioned to be supplemented by the heat and flame from the main burner. Pilot stability is supported by the main burner flame to maintain a constant pilot flame even in adverse wind conditions. The thermocouple is so positioned to be energized not only from the pilot burner but also by the radiated heat from the main burner flame. This relation of pilot and thermocouple is considered new and highly efficient.

Associated with the foregoing special relation of pilot and thermocouple is a stabilizing shield to house the pilot and the thermocouple, said shield having a sloping top, a rear portion having openings to receive the pilot and thermocouple, and two closed sides, the bottom of the shield being open.

Background

In seeking to design a gas burner assembly to complement our gun type oil burner and yet be equally competitive in price and efficiency, it was found by extensive study and test that while the several well known gas-using elements work excellently with each other in normal relationship, they have to have those relationships altered to make the assembly substantially fool-proof when the units must be exposed to the weather. As a typical example, a thermocouple is damaged by too much heat but if the heat is too low this tiny but essential part will fail to generate the proper number of millivolts. But by placing the thermocouple in an unusual location where it is energized by the pilot and supported by the main burner flame it works excellently. In such position the thermocouple and the pilot flame must be shielded at back, top and on both sides but the stabilizing shield must be open down toward the burner flame and forward in the direction of that flame.

Brief summary

This invention relates to gas burners and particularly to burner assemblies for fire clay lined incinerators which provide complete cremation of poultry refuse weighing from 600 to 1,000 pounds in from three to four hours, using perhaps as much as 250,000 B.t.u.'s. Many of the parts are well known and old but the specific space relationship arrangements are the result of extensive study and test in order to make the units work reliably even

2

under severe climatic conditions as the units are intended for outside use and must be designed to require minimum attention.

Figures

5 In the drawings:
FIGURE 1 is a side elevation of the assembly taken just inside of the near long bracket.

10 FIGURE 2 is a plan view omitting the two weather protecting shields.

15 FIGURE 3 is a front elevation looking from within the incinerator toward the discharge end or head of the burner.

20 FIGURE 4 is a section taken on line 4—4 of FIGURE 3.

25 FIGURE 5 is a section through the plug in the end of the lighter tube.

Description

The readily obtainable standard parts include a spring-wound four-hour timer 10, a safety valve 11 which closes the gas supply entering at 12 in the event of failure of the pilot or burner, an atmospheric venturi inshot burner 14 with the usual draft control 15 near the intake 16 of the venturi. Other parts which are old are the burner head 20, the pilot 22 fed from the safety valve 11 by the copper tube 25 and the thermocouple 26 connected electrically to the safety valve 11 by wiring within the tube 27. In place of the usual lighting arrangement, a strip lighter tube 30 having a longitudinal plurality of holes 31 is provided and forms a somewhat downwardly flow of gas because of a drilled plug 32 within the end of the tube 30. This lighter tube receives gas from the safety valve 11 and terminates slightly forward of the burner head 20, thus well avoiding scorched fingers.

30 35 The supporting structure for the various parts is shown in all four figures. To the curved wall 35 of the incinerator, two vertical angle irons 36 and 38 are welded as at 40, affording support for two large rearwardly extended tapered brackets 41 which at their forward smaller ends 42 are bent inward as at 44 and then are bolted as at 43 to the safety valve 11 thus supporting the assembly at its rear portion while the burner head 20 rests upon a transverse strap 50 to which it is welded as at 51, the strap being bolted to the brackets 41 as at 52.

40 45 The smaller rain shield 53 (FIG. 1) is riveted as at 54 to the angle iron 36 and 48 to afford protection and yet allowing ready access to the parts shown at the top of FIG. 4. The larger snow and rain rear shield 55 is riveted as at 56 to an inverted stirrup 58 rising from the two brackets 41.

50 55 Referring now to FIG. 3, the opening 60 in the incinerator wall 35 is circular and co-axial with the burner head 20. The position of the head 20 of the burner with respect to this orifice is critical because if the burner projects too far, the temperature within the incinerator is too high whereas too slight a projection causes insufficient temperature to energize the thermocouple.

Since this unit is used to burn trash and not just to generate heat, the demand for secondary air is much greater than can be provided by the venturi of the burner. The temperature may exceed 1000° or 1200° F. In addition to providing secondary air, this movement of air over the burner keeps the burner and the related parts cool because of the passing air current.

60 65 If the burner head 20 were placed too close or too far into the hole, the intense heat from the burning mass itself would exceed the maximum tolerance of the thermocouple, and thereby cause rapid deterioration of same. Too close positioning would also result in early deterioration and damage permanently to the burner itself.

The circular opening should be between 3½" and 6" in diameter and the burner head should be about an inch

short of the opening in order to provide adequate intake of air to the burner and to supply enough oxygen to burn the trash in the incinerator.

In order to diffuse the burner flame, two strips of stainless steel, one smooth 65, and the other corrugated 66, are wound spirally and fitted within the burner head leaving an opening 67 of about an inch in diameter. This creates an irregular intact surface for the gas release and insures against blowing out of the flame.

The stabilizing shield 70 is of great importance as it creates within its confines a pocket of relatively still air separated from the air moving rapidly over the shield, hence protecting the pilot flame from extinction and insuring that the temperature at the thermocouple is stabilized and therefore will generate the necessary number of millivolts to hold the safety valve open; in other words to provide a temperature reflecting pocket to stabilize the pilot flame as well as to properly support the thermocouple. This stabilizing shield, as best seen in FIGURE 4, has an 18° sloping upper surface 71 which will position the end of the thermocouple 26 very slightly above the line of flame from the burner and slightly within the curved surface of the incinerator when continued through the orifice 60. The shield has also a nearly vertical back wall 72 and two side walls 73 and 74. The pilot flame as usual is directed both vertically downward to be tangent to the main flame and horizontally sideways as at 75 to heat the thermocouple.

Referring now to FIGURE 5, since most incinerators have high stacks, the suction through the opening 60 is great and hence it is necessary to have this stabilizing shield 70 and to direct a flame within the confines of the shield. To this end and to insure that gas will flow through the holes 31, the plug 32 hollow as at 81 at its rear end and having a radial hole 82 directed downward not only slows the flow while increasing the pressure but passes a flame under the near side of the stabilizing shield and provides for the pilot lighting.

To start the device, the timer 10 is first set, then the red button 83 at the top of the safety valve 11 is pressed down and the button 84 of the strip lighter simultaneously held up, these two actions together admitting gas to the pilot 22 and to the strip lighter 30, but not to the burner 14. Next the lighter 30 is lighted as the operator still holds both buttons. The flame coming from the end of tube 30 through radial passage 82 being directed below the near wall of the stabilizing shield 70 ignites the pilot.

After holding the buttons a sufficient number of seconds to energize the thermocouple 26, both buttons are now released which shuts the gas off from the strip lighter and opens the flow of gas to the main burner. The main burner is now ignited by the downwardly directed flame from the pilot 22. Since the pilot flame continues at all times until the timer shuts off the gas, the sidewise flame from the pilot directed toward the thermocouple 26, plus the heat from the main burner and with the aid of the stabilizing shield maintains the required temperature for the thermocouple.

What I claim is:

1. A gas burner assembly comprising:
  - (A) a main gas burner having a burner head adapted to project a flame forwardly therefrom;
  - (B) a passageway connecting the burner to a source of gas;
  - (C) a safety valve in said passageway for shutting off the gas in event of flame failure;
  - (D) a pilot adjacent the burner discharge head;
  - (E) a thermocouple proximate the pilot and coupled to actuate said safety valve;
  - (F) a stabilizing shield assembly housing the pilot and the thermocouple; said shield having a sloping top, a rear portion having openings receiving the pilot and the thermocouple, and two closed sides; the bottom of the shield being open; and means mounting the assembly on the burner head so as to extend forward of the burner head with the top sloping down towards and terminating closely adjacent the surface of said flame; and
  - (G) said thermocouple and pilot thereby being so positioned that the thermocouple is energized not only from the pilot but also by the radiated heat from the main burner flame and additionally the pilot is energized by the flame from the main burner whereby pilot stability is supported by the main burner flame to maintain a constant pilot flame regardless of adverse wind conditions.
2. The assembly of claim 1 plus an incinerator having a wall with a circular orifice through which the burner flame passes, the discharge head being spaced from and concentric with said orifice for entry of secondary air, and said shield extending into the orifice.
3. The assembly of claim 1 in which the thermocouple is tilted 18° with its tip at a level with the highest point of the interior of the burner head.
4. The assembly of claim 2 in which the orifice has a diameter of between 3½" and 6".
